UNITED STATES PATENT OFFICE.

JOHN C. GOSS AND ANDREW T. HANSEN, OF DETROIT, MICHIGAN.

CANVAS-STRETCHER.

No. 876,345.

Specification of Letters Patent.

Patented Jan. 14, 1908.

Application filed July 31, 1907. Serial No. 386,348.

To all whom it may concern:

Be it known that we, JOHN C. GOSS and ANDREW T. HANSEN, citizens of the United States of America, residing at Detroit, in the county of Wayne and State of Michigan, have invented certain new and useful Improvements in Canvas-Stretchers, of which the following is a specification, reference being had therein to the accompanying drawings.

This invention relates to means for applying canvas or the like as covering to the decks, cabin floors, etc., of a vessel, whereby it may be drawn as taut as desired and cut while in place, without waste.

The invention consists in the matters hereinafter set forth, and more particularly pointed out in the appended claims.

Referring to the drawings, Figure 1 is a view in perspective of a portion of a ship's deck, with adjoining rail and side, together with a device for stretching canvas thereon which embodies the features of the invention. Fig. 2 is a view in perspective of the end portion of a clamp. Fig. 3 is a view, partially in section of a state room wall and floor, showing the application of a clamp to an inclosed floor or deck space.

In the drawings, 1 represents a portion of a ship's deck with adjacent rail 2, scupper strake 3 and fender strake 4, secured to the ship's side 5.

A bolt or strip of canvas 6 is also shown athwartship on the deck, its end, not shown, being permanently secured to the opposite side of the deck. To draw the canvas taut, a clamp is secured transversely on the strip near the ship's rail. This clamp consists of a flat lower member 7 and upper member 8, of equal size and rectangular form longer than the width of the canvas, preferably of wood. The upper member has depending marginal flanges 9 conveniently made by securing flat metal strips to the edges of the board or plank by screws 10 or the like, the projecting portions 11 being slightly flared or rolled outwardly. The jaws or members are secured together at each end by hand bolts 12, each of which passes centrally through metal cross-straps 13 screwed or nailed to the upper face of the upper member across its end, and the bodies of the member, and has screw-threaded engagement with the metal bar 21 which is secured on the under side of the lower member across the end. A collar or flange 14 integrally formed on the bolt en-

gages the cross-strap 13, so that the clamp is drawn together when the bolt is turned, as by a suitable handle 15.

The length of each of the upper cross-straps 13 is greater than the width of the clamp, and the projecting ends are each apertured or formed with an eye 16.

A tail block 17 of a tackle 18 having single, double or multiple purchase, is hooked into each eye, and the fall block 19 is provided with a hook 20 adapted to pass under the ship's rail and hook over the fender strake 4 on the ship's side.

In applying the clamp, the lower member 70 is slipped through under the canvas strip, near the ship's side, and the upper member placed over it and drawn down by the bolts, the flanges folding the canvas and gripping it tightly without injuring or puncturing it. The tackle is then hooked on and by setting up on the ropes, the canvas is drawn as taut as desired, and the strip tacked to the deck beyond the clamp which may be readily released and removed, the slack occasioned by the folding around the flanges being overcome by pulling the strip slightly tighter than is finally desired.

In using the clamp in a state room, where the tackle is not available, a pair of scantlings 22 are adjusted as shown in Fig. 3 with their adjacent ends abutting and their outer ends bearing against the clamp and wall, the toggle joint effect straining the canvas taut readily, and allowing it to be permanently secured outside of the clamp as before.

The pull or thrust directly in line with the canvas and at each margin of the strip, enables the user to increase or lessen the strain so that canvas may be drawn evenly over the irregular or curved surfaces which are the result of the sheer lines of a boat, and which do not admit of the use of the ordinary forms of stretchers available for laying carpets or the like on flat, plane surfaces. Furthermore, the gripping of the fabric uniformly throughout its width at every point, transmits the pull directly to every part of the warp, so that the great strain to which the canvas is subjected is evenly distributed and does not weaken any particular portion.

What I claim as my invention is:—

1. A canvas stretcher comprising a pair of parallel, flat rectangular clamping jaws, provided with longitudinal marginal flanges on the upper jaw adapted to close over the corresponding edges of the lower jaw, a clamp-

ing hand bolt having a shoulder, said bolt passing through one of said jaws and having screw-threaded engagement with the other of said jaws, and a pair of falls, whose tackle blocks are adapted respectively to detachably engage the clamping jaws at either end and to hook over a fender strake or the like on a ship's side.

2. A canvas stretcher comprising a pair of parallel, wooden clamping jaws, having longitudinal, flat metal flanges secured on the side margins of the upper jaw, adapted to close over the side margins of the lower jaw, a metal cross bar secured across the under- 15 side of the lower jaw near each end, a metal cross strap secured on the upper side of the upper jaw near each end, a clamping hand-bolt passing through each cross strap and jaw, having screw-threaded engagement with the corresponding cross bar, eyes formed in each cross-strap extending over the margin of the jaw, and a pair of falls, whose tackle blocks are severally adapted to engage the strap eyes and hook over an adjacent fender 20 strake on the ship side.

3. A canvas stretcher comprising a pair of corresponding wooden clamping jaws, whose longitudinal margins are parallel, flat metal flange bars secured on the longitudinal margins of the upper jaw, whose depending edges are slightly outwardly flared, and adapted to close over the corresponding margins of the lower jaw, a flat metal cross-bar secured across the underside of the lower jaw at each 30 end thereof, a flat metal cross strap secured on the upper side of the upper jaw across each end thereof, the corresponding apertured ends of said straps projecting beyond the

jaws, a clamping bolt passing centrally through each strap and the jaws, having a collar integral with the bolt against the upper face of the strap, and having screw-threaded engagement with a central aperture in the corresponding cross-bar, and a fall secured by a hook on one tackle block to the apertured end of a cross-strap and by a hook on the other block to an adjacent portion of a ship's fender strake.

4. A canvas stretcher comprising a pair of flat, rectangular, wooden clamping jaws placed face to face, outwardly flared flange irons secured on the longitudinal edges of the upper jaw, extending over the corresponding edges of the lower jaw throughout their length, metal cross-straps secured on the upper side of the upper jaw across each end, an eyelet integral with each strap projecting from one edge of the jaw, metal cross bars secured on the underside of the lower jaw across each end, shouldered hand bolts passing centrally through each end of the jaws, bearing against the cross-straps and having screw-threaded engagement with the cross-bars, a tail block hooked into the eye of each cross-strap, multiple blocks having hooks 65 adapted to engage a fender strake, and ropes, each attached to the tail blocks and rove through the companion multiple block and the said tail block.

In testimony whereof we affix our signatures in presence of two witnesses.

JOHN C. GOSS.

ANDREW T. HANSEN.
